UNITED STATES PATENT OFFICE.

FRANK MACHAVA, OF GREENSBURG, PENNSYLVANIA.

VICE.

1,070,049.

Specification of Letters Patent. Patented Aug. 12, 1913.

Application filed April 6, 1912. Serial No. 689,052.

To all whom it may concern:

Be it known that I, FRANK MACHAVA, a citizen of the United States of America, residing at Greensburg, in the county of Westmoreland and State of Pennsylvania, have invented certain new and useful Improvements in Vises, of which the following is a specification, reference being had therein to the accompanying drawing.

10 This invention relates to vises, and the primary object of my invention is to provide a vise that can be easily and quickly adjusted for positively holding pipes and other structures whereby they can be operated 15 upon.

20 A further object of this invention is to provide a strong and durable vise with various kinds of gripping jaws whereby a pipe can be positioned and conveniently operated upon.

25 I attain the above objects by a mechanical construction that will be hereinafter specifically described and then claimed, and reference will now be had to the drawing, where-

25 in like numerals denote corresponding parts throughout the several views, in which:—

Figure 1 is a front elevation of the vise partly broken away and partly in section, Fig. 2 is a side elevation of the same partly 30 broken away and partly in section, Fig. 3 is a horizontal view of the vise taken on the line III—III of Fig. 1, Fig. 4 is a similar view taken on the line IV—IV of Fig. 1, Figs. 5 and 6 are perspective views of de- 35 tached jaws, Fig. 7 is a perspective view of a detached modified form of jaw, and Fig. 8 is a similar view of a jaw attachment.

40 A vise in accordance with this invention comprises a base block 1 having an integral base plate 2 adapted to be secured to a suitable support 3 by fastening means, such as screws (not shown) passing through openings 4 provided therefor in the base plate 2. The rear side of the base block 1 is pro-

45 vided with uprights 5 having the lower ends thereof connected by a transverse bar 6 and the upper ends thereof by a cross head 7. Secured to the cross head 7 by screws 8 or other fastening means is a forwardly extending bracket 9 and adjustably mounted in said bracket is a vertical screw 10 having the upper end thereof provided with a hand wheel 11. The lower end of the screw 10 has a head 12 retained in engagement with a 50 jaw body 13 by a plate 14 that is attached to the jaw body 13 by screws 15 or other fas-

tening means. The lower edge of the jaw body 13 has a vertical rectangular frame 16 and said frame has a vertical guide 17 that slides through an opening 18 provided therefor in the bracket 9. The frame 16 has vertical rails 19, at the rear side thereof, engaging the rear side of the uprights 5. The frame 16, adjacent to the jaw body 13, has guides 20 engaging the front side of the uprights, the rails 19 coöperating with the guides 20 in movably holding the jaw body 13 upon the uprights 5.

60 The underneath side of the jaw body 13 has a longitudinal socket 21 confronting a similar socket 22 in the base block 1 and arranged in said sockets and retained therein by set screws 23 are the tongues 24 of jaws 25. Each jaw has a concave serrated or toothed seat 26 for gripping the surface of 65 a pipe. When it is desired to grip a very small pipe or rod, a convexo-concave attachment 27 is placed in engagement with the jaw 25 of the jaw body 13, said attachment having a tongue to fit in a recess 28 provided 70 therefor in the jaw 25.

75 As illustrated in Figs. 5 and 6, I can resort to the use of jaws 29 and 30, the jaw 29 being bifurcated, as at 31 to receive the jaw 30, whereby pipes or rods of various sizes 80 can be held between the jaws. In this instance, the gripping surfaces of the jaws 29 and 30 longitudinally aline with an opening 32 between the uprights 5, while in Fig. 2 the gripping surfaces are arranged longitudinally of the base block 1. By using the jaws illustrated in Fig. 2, a pipe is held longitudinally of the base block 1 and by using the jaws 29 and 30 a pipe is held at right angles or transversely of the base block 1, 85 the pipe in some instances extending through the opening 32. The jaws 29 and 30 have concave gripping surfaces, while the modified form of jaw illustrated in Fig. 7 has a 90 V-shaped gripping surface.

95 It is thought that the operation and utility of the vise will be apparent without further description, and while in the drawing there is illustrated a preferred embodiment of the invention, it is to be understood that the 100 structural elements thereof are susceptible to such changes as fall within the scope of the appended claim.

105 What I claim is:—

110 A vise comprising a base block, a jaw detachably connected thereto, uprights carried by the rear edge of said base block, a cross

head connecting said uprights, a bracket carried by said cross head, a screw adjustably mounted in said bracket, a jaw body supported by said screw, a jaw detachably connected to said jaw body and confronting the jaw of said base block, a rectangular frame carried by said jaw body, rails carried by said frame and engaging the rear sides of said uprights, guides carried by said frame

and engaging the front side of said uprights, 10 and a central guide carried by said frame and movable through said cross head.

In testimony whereof I affix my signature in the presence of two witnesses.

FRANK MACHAVA.
